NEWMAN A. FOSS AND JOHN M. GRAY, OF CLENDENIN, MONTANA
TERRITORY.

ROASTING-FURNACE.

SPECIFICATION forming part of Letters Patent No. 293,002, dated February 5, 1884.

Application filed September 4, 1883. (No model.)

To all whom it may concern:

Be it known that we, NEWMAN A. FOSS and JOHN M. GRAY, of Clendenin, in the county of Meagher and Territory of Montana, have 5 invented a new and Improved Roasting-Furnace, of which the following is a full, clear, and exact description.

The object of the invention is to improve roasting and slagging furnaces, as hereinafter 10 described, and pointed out in the claims.

Reference is to be had to the accompanying drawings, forming part of this specification, in which similar letters of reference indicate corresponding parts in all the figures.

15 Figure 1 is a longitudinal sectional elevation of our improved furnace. Fig. 2 is a similar section of part of the tube and the feeding apparatus on an enlarged scale. Fig. 3 is a similar section through the reverberatory furnace and receiving-chamber and part 20 of the tube, also on an enlarged scale. Fig. 4 is a transverse section on the line *x x* of Fig. 3, and Fig. 5 is a transverse section of the tube on the line *y y* of Fig. 1.

25 We arrange a long tube, *a*, between the receiving-chamber *s* and the chimney *c*, made in preferably four sections, which are successively smaller in diameter from the furnace to the chimney, forming inside ledges at the 30 junctions, down which the ore falls in passing from one section to another. The outside shell of the tube is made of boiler-iron, and the sections are joined together by strong rings of cast-iron *d*, having an offset to correspond 35 with the sizes of the two sections to be joined. The inside is lined with fire-brick, and there are four spiral projecting ribs, *e*, of the same material, to feed the ore along the tube. The brick of which ribs *e* are formed are set with 40 their longitudinal projecting side faces in line with the axis of the cylinder, so that these faces form a series of steps down which the ore falls for more complete exposure to the heat, as will readily be understood. The tube 45 is mounted by ring-rails *f* on grooved rollers *g* for its support, and on which it is to be revolved by power applied to the pinion *h*, and working the toothed rim *i*, attached to the tube. The tube is arranged on a slight inclination 50 from the furnace up to the base of the flue *c*,

into which it discharges through the lateral opening *j*, in which there is a conveyer-tube, *k*, containing a screw, *l*, the shaft of which is attached to a cross-bar, *m*, of the tube, so as to be revolved by the tube. From the upper end of said tube *k* there is a spout extending up through the base of the flue, to which the ore is delivered from the hopper *o*. The boxes *p* for the grooved roller-bearings are secured to the supporting-beds by bolts *q*, that are prolonged considerably above the boxes, in order that the boxes may be raised and packed up in case it may be desired to alter the inclination of the tube for varying the pitch to accelerate or retard the movement of the ore. 65 From the lower end of the tube the ore discharges into a receiving-chamber, *s*, lined with refractory material, and having an inclined hearth, *t*, onto which the ore falls. This furnace is built on a strong foundation, and has 70 two working-doors, *u*, on each side, and on each side, above the working-doors, is another door, *v*, to be opened, when required, to admit cold air to regulate the temperature in the tube. The front wall, opposite to the end of the tube, has another door, *w*, (dotted Fig. 3,) to admit cold air, and another door, *x*, is provided under the tube for the same purpose. 75

The receiving-chamber *s* discharges into a reverberatory furnace, *y*, in which is a cast-iron pan, *z*, resting on brick or stone piers *a'*, and lined with fire-brick *b'*, forming the fusing-hearth. At each end of the pan is a cast-iron water-jacket, *c'*, resting in the pan, and having the proper pipe-connections for maintaining a circulation of water therein for the protection of the bridge-wall *d'* and the back wall, *e'*, from the extreme heat. Back of the fusing-hearth, at *f'*, there is an opening at each side for admitting the air for the furnace, to cause it to pass along under the pan for keeping it cool, and for heating the air for preparing it for more effectual combustion, the fuel-door *g'* and the ash-pit door *h'* being closed in order to cause the air to enter in this way. The 90 arch of the reverberatory furnace is contracted at the end next the receiving-chamber, the object of which is to bring the flame gradually nearer the fusing-hearth as it leaves the more heated part of the furnace, thus giving a uni- 95 100

form heat throughout. The furnace *y* and the receiving-chamber *s* are braced by side stays, *j'*, and rods *h'*.

The ore, after being crushed and pulverized 5 to a fine powder and mixed in suitable proportions for treatment, is taken to the hopper, from which it is conveyed into the cylinder or revolving part of the furnace by the screw-conveyer *l*, which turns with the cylinder. By 10 the inclination of the cylinder each revolution advances the ore gradually from the cooler to the more heated part of the furnace. When the ore has been raised sufficiently high on the lines of projecting tiles *e*, it falls off in finely- 15 divided streams through the hot gases passing up the cylinder in such a way that no particle can escape full exposure to the oxidizing influence required for proper calcination. The ore having become sufficiently heated for the 20 expulsion of the sulphur, arsenic, and other metals capable of being separated by the combined action of heat and atmospheric air, and the substitution of oxygen for the metals so expelled, the ore arrives at the receiving- 25 chamber *s* in the best possible condition for treatment, presently to be described. The heat evolved by the combustion of the sulphur and arsenic assists in roasting the ore in the upper part of the cylinder. The receiving-chamber 30 *s* is the receptacle for the roasted ore coming from the cylinder. Here the ore is exposed to a much higher temperature, and the roasting is continued until the charge undergoing slagging in the reverberatory furnace is withdrawn. Then the charge in the receiving-chamber 35 is advanced by the workman, with tools applied through the working-doors *u*, to the fusing-hearth *v*. During this operation the furnace-men regulate the heat in the receiving- 40 chamber and cylinder by opening or closing the doors *v* of the receiving-chamber, allowing the introduction of more or less cold air.

The ore having reached the fusing-hearth, fusing and agglomeration take place at once, 45 and the ore is withdrawn from the furnace through the working-doors *u* as a silicate of lead containing all the precious metals and in the best possible condition for subsequent treatment in the blast-furnace; or by raising 50 the working-doors a few inches above the fusing-hearth and providing the furnace with a tap for the discharge of the slag and bullion and adding the necessary flux, reduction will take place and the separation of the slag and 55 bullion will be complete without further treat-

ment. The flame, after doing its work in the reverberatory furnace and receiving-chamber, roasts the ore in the cylinder, which serves the part of a flue, thus economizing fuel.

This improved furnace affords the following 60 advantages as compared with others: The automatic feed gradually brings the ore to the furnace, giving a steady and constant feed; the length of the cylinder giving the ore sufficient time for desulphurizing before arriving 65 at the fusing-furnace, the diminishing form of the cylinder concentrating the heat in the flue end; the adjustable-bearing arrangement, whereby the cylinder may have more or less inclination for passing the ore faster or slower 70 through the cylinder as the ore needs more or less roasting; the constant agitation of the ore effected by the projecting lines of tile in the cylinder keeping the ore constantly falling through the hot gases passing up the cylinder; 75 the facility afforded for the escape of any metals reduced or slagged by the inclined hearth of the receiving-chamber into the reverberatory furnace; the facility of regulating the heat in the cylinder by allowing the introduction of cold air through the receiving-chamber; the iron pan forming the bottom of 80 the reverberatory furnace arranged for not absorbing the fused metal and being more readily and easily repaired; the arrangement for 85 allowing the cold air to pass under the furnace, keeping the bottom cool and warming the air before reaching the fuel; the greater economy of treatment by lessening the cost of stirring of the ore during roasting by the rolling of the tube, instead of by manual labor; the economy of fuel by roasting and slagging 90 at the same time and using the evolved gases to assist in roasting the ore.

Having thus described our invention, we 95 claim as new and desire to secure by Letters Patent—

1. In combination with the sections of tube *a*, the metallic bands or rings *d*, offset to fit closely over the joint or junction of two adjacent sections, as shown and described.

2. The combination, with tube *a*, lined on the inside with refractory material, of spiral ribs formed of brick laid to make a succession of steps, as and for the purpose specified. 105
